MULTI-STAGE MICRO-CIRCUIT CLEANING STATION

Howard M. Layton, Ossining, N.Y., assignor to
Interlab, Inc., Pleasantville, N.Y.

Filed May 13, 1970, Ser. No. 22,949

Term of patent 14 years

Int. Cl. D15—05

U.S. Cl. D49—11

FIG. 1 is a front perspective view of my design for a multi-stage micro-circuit cleaning station;

FIG. 2 is a rear elevational view of my design;

FIG. 3 is one end-view of my design, the other end being identical;

FIG. 4 is a top plan view of my design.

I claim:

The ornamental design for a multi-stage micro-circuit cleaning station, as shown and described.
